UNITED STATES PATENT OFFICE.

WESLEY W. SCHETTLER, OF SPRINGFIELD, OHIO, ASSIGNOR TO THE FOOS GAS ENGINE COMPANY, OF SPRINGFIELD, OHIO, A CORPORATION OF OHIO.

SAFETY DEVICE FOR PREVENTING PASSAGE OF FLAME.

Application filed April 4, 1925. Serial No. 20,854.

This invention relates to devices for preventing the passage of flame to a source of combustible mixture, it particularly relating to a device for preventing the flame occasioned by backfire from the cylinders of an internal combustion engine from passing to the crank case of the engine in an arrangement wherein a connection is made between the crank case and the cylinders for the purpose of eliminating the vapor in the crank case.

An object of my invention is to provide a safety device of the character referred to which will be simple in construction and effective in its operation.

The invention consists in providing a safety device constructed with a normally open check valve located in the connection between the source of combustible mixture and the point of delivery thereof which is closable by the pressure of the gases occasioned for instance by backfire, in connection with a passageway between the valve and the point of delivery of a tortuous character calculated to retard the flame of backfire until the valve has been closed by the pressure of the gases; the arrangement being further of such a nature that the passageway through which the flame must travel to pass the check valve is considerably longer than the length of the passage between the source of pressure occasioned by backfire and the valve head, the valve head forming in fact a part of the passageway.

In the accompanying drawings:

Fig. 1 is a vertical section of a device embodying the improvements.

Fig. 2 is a section on the line 2—2 of Fig. 1.

One of the instances of danger is in connection with internal combustion engines in which a passageway is provided between the crank case and the intake manifold. In gas engines so equipped it sometimes happens that a backfire occurs which causes an explosion in the crank case, thereby wrecking the engine. To overcome the danger of the passage of flame in this and other structures I have devised the following arrangement.

1 represents a portion of the intake manifold and 2 a portion of the crank case. 3 and 3' represent the two sections of a tubular connection between the crank case and the manifold joined together in any suitable way. Each of these sections has a flange 3'' so that they may be bolted, respectively, to the manifold and crank case and the lower section 3' also preferably has a removable plate 4 by which access may be obtained to the interior thereof. Formed integrally with the lower section 3' is a guide 5 and its spider like supporting arms 6. Slidably mounted in the guide 5 is a valve stem 7 having on its upper end a valve 8 cooperating with an interior valve seat 9 near the upper end of the section 3'. Also integrally formed with the section 3' is a horizontally perforated wall 10 having a central threaded opening 11 in which is screwed a spring supporting stem 12. The lower end of this stem 12 has also screwed thereon a perforated disk 14 which is seated against an interior shoulder 15 near the lower end of said section 3'. A nut 16 on the lower end of the stem 12 serves to hold it in different positions of adjustment. The valve stem 7 has a flanged collar 17 pinned thereto and also pinned to the upper end of the support 12 is a flanged collar 18. Interposed between and supported by these collars is a coil spring 19 which tends normally to hold the valve 8 in open position shown, the flange on the collar 17 coacting with the lower end of the guide 5 to form a stop for the opening movement of the valve.

Secured to a boss 20 on the upper face of the valve 8 is a tube 21 which extends through the section 3 within a short distance 90 of the upper end thereof. Secured to an in-turned flange 22 on the upper end of the section 3 is a second tube 23 which projects through the outer tube 21 in spaced relation therewith to a point within close 95 proximity to the boss 20.

In operation the valve 8 normally stands in the open position as indicated under the action of the spring 19 and the vapor in crank case passes upwardly between the 100 casing section 3 and the tube 21, thence downwardly between the tubes 21 and 23.

and thence upwardly through the tube 23. If backfire occurs the air and vapor in the tube 23 are compressed exerting a pressure upon the head 20 of the valve 8 thereby closing the valve against tension of the spring. When such back fire occurs there is a rise of pressure in the passage 1. This is transmitted as a pressure wave through the tube 23, giving up its velocity head against the head of the check valve 20 and closing the check valve 8 on its seat 9 against the spring 19. To this velocity head impulse is added a reaction pressure also tending to close the valve as there can be no passage of gases through the annulus bounded by the walls 21 and 23 until a sufficient reaction is set up against 20. These changes of flow, in addition to providing an acting and reacting force for the closure of the valve, considerably extend the time necessary for the burning combustible gases to pass through the passage between the walls 21 and 23 to reach the seat 9 and by making the tubes 21 and 23 of suitable length any discrepancy between the rate of flame propagation, the rate of gaseous flow and the rate of acceleration of the valve in closing can be compensated.

While I have shown a spring pressed valve, I do not desire to be limited to such an arrangement of valve as any valve which is arranged to stand normally open but close under pressure may be used to accomplish the result. Neither do I desire to be limited to the exact form of tortuous passageway between the valve and the intake manifold as any passageway which will delay the flame of backfire to permit the pressure occasioned by the backfire to close the valve in advance of the flame is contemplated.

While I have described the invention in connection with the cylinders and crank shaft of an internal combustion engine, yet the invention is applicable to other structures in which there is danger of ignition of the combustible mixture flowing from the source of supply.

Having thus described my invention, I claim:

1. In a fire check device for combustible fluid having a valved opening and a passageway leading from said opening to a point of discharge, of a normally open valve controlling said opening, said valve forming a part of said passageway at an intermediate point in said passageway whereby back pressure of gasses in said passageway acts upon said valve at a point removed from the opening controlled by the same.

2. In a fire check device for combustible fluid, a normally open valve closable under pressure and controlling an opening therein, and a tortuous passageway between said opening and the place of discharge for

the fluid, said valve being arranged to be subjected to back pressure in said passageway at a point remote from said opening.

3. In a fire check device for combustible fluid, a normally open valve closable under pressure in said device, said device having a passageway between said valve and the place of discharge for said fluid extending away from said valve then toward the valve and then again away from said valve, said valve being arranged to be subjected to back pressure in said passageway at a point remote from said opening.

4. In a fire check device for combustible fluid, a normally open valve closable under pressure in said device, and a pair of telescoping tubes in said device between said valve and place of discharge of said fluid to form a tortuous passageway, said valve being arranged to be subjected to back pressure in said passageway at a point remote from said opening.

5. In a fire check device for combustible fluid, a normally open valve closable under pressure in said device, a tube secured to said valve and extending toward the place of discharge for the fluid to form a passageway on the outer side of said tube, and a second tube secured to said device and extending within the said first mentioned tube to form a passageway leading back towards said valve and thence through said second tube.

6. In a fire check device for combustible fluid, a valve in said device, a spring for holding said valve normally open, an open ended tube connected with said valve on the discharge side thereof to form a passageway between the walls of said device and said tube, and a second open ended tube carried by said device and leading from the point of discharge for said fluid towards said valve to form a return passageway between said tubes and thence through said second tube.

7. In a fire check device of the character described, a guide in said device, a valve having a stem slidably mounted in said guide, and an adjustable support carried by said device, a spring between said support and said valve stem normally tending to hold said valve open, an open ended tube connected with said valve, and a second open ended tube supported by said device telescoping said valve tube, said tube forming a tortuous passageway between the valve and said place of discharge.

8. A fire check device for combustible fluid having a valved opening and a normally open valve for said opening, and means intermediate said valved opening and the outlet for said fluid whereby back pressure of the fluid due to ignition thereof will act upon the valve at a point in the

passage remote from said opening for the purpose of closing the valve.

9. A fire check device for combustible fluid having a valved opening and a normally open valve for said opening, and a tortuous passageway between said opening and the outlet for said fluid arranged so

that back-pressure of the fluid due to ignition will act upon the valve at a point in said tortuous passage remote from said valve for the purpose of closing the valve. 10

In testimony whereof, I have hereunto set my hand this 2nd day of April, 1925.

WESLEY W. SCHETTLER.
